CLAIM

I claim the ornamental design for a pet bowl, as shown and described.

DESCRIPTION

FIG. 1 is a front, side perspective view of a pet bowl of the present design, shown in a collapsed state;

FIG. 2 is a side view thereof, the opposite side being substantially a mirror image;

FIG. 3 is a front view thereof;

FIG. 4 is a top view of the pet bowl, shown in an expanded state;

FIG. 5 is a bottom view thereof;

FIG. 6 is a side view thereof;

FIG. 7 is accurately a front view for both the pet bowl of the first embodiment, when in an expanded state, as well as for the pet bowl of the second embodiment, when in an expanded state;

FIG. 8 is a front perspective view of the pet bowl according to a second embodiment, shown in an expanded state;

FIG. 9 is a top view thereof;

FIG. 10 is a bottom view thereof;

FIG. 11 is a side view thereof; and,

FIG. 12 is a back view thereof.

The broken lines throughout the drawings form no part of the design claim, but are employed to depict, in some instances, exemplary elements of the pet bowl that form no part of the claimed design but that are shown for purposes of illustration, or in other instances, to illustrate what would be the lines of crease along which folding of the bowl occurs when in a collapsed state.
